**COMBINED SWITCH AND INDICATOR HOOD
THEREFOR**

David E. Clarke, Attleboro, and Robert W. Peterson,
North Attleboro, Mass., assignors to Texas Instruments
Incorporated, Dallas, Tex., a corporation of Delaware

Filed Sept. 18, 1967, Ser. No. 8,627

Term of patent 14 years

Int. Cl. D13—03
U.S. Cl. D26—13

Fig. 1.

Fig. 2.

FIG. 1 is a perspective view of the combined switch and indicator hood therefor showing our new design with the button in a depressed position, the opposite side being a mirror image thereof.

FIG. 2 is a perspective view with the button in an extended position and with the contrasting top of the button open to view.

The dominant features of our new and ornamental design are shown in solid lines in the drawing.

We claim:

The ornamental design for a combined switch and indicator hood therefor, substantially as shown and described.
